UNITED STATES PATENT OFFICE.

WILLIAM M. SCHOLL, OF CHICAGO, ILLINOIS.

INSTEP-ARCH SUPPORT.

1,142,850.

Specification of Letters Patent. Patented June 15, 1915.

Application filed January 29, 1912. Serial No. 674,058.

To all whom it may concern:

Be it known that I, WILLIAM M. SCHOLL, a citizen of the United States, residing at Chicago, in the county of Cook and State of Illinois, have invented certain new and useful Improvements in Instep-Arch Supports, of which the following is a specification.

My invention relates to improvements in instep arch supports, and has for its salient object to provide a novel construction of arch support in which the supporting surface is given form by the joint effect of two plates, the one a base plate of appropriate relatively large extent, and the other an auxiliary plate of relatively lesser extent, partly overlying the main plate and extending laterally beyond the main plate to constitute a wing extension upwardly curved to conform to the inner plantar surface of the foot arch.

Another object of my invention is to so construct the parts of the device that an adjustment thereof can be readily effected; the two plates, to this end, being made readily separable or detachable so that each plate may be treated separately, at the time the arch is fitted to the purchaser's foot, to give each plate the most appropriate shape to fit the foot of the individual user.

Other objects of my invention will become apparent to those skilled in the art from the following description taken in conjunction with the drawings, in which—

Figure 1 is a plan view of the main and auxiliary plates, with the cover piece shown in dotted lines; Fig. 2 is a transverse section on line 2—2 of Fig. 1, with cover piece in place; Fig. 3 is a longitudinal section on line 3—3 of Fig. 1; and Fig. 4 is a perspective view of the two plates separated.

In the drawings 5 indicates the main plate, preferably shaped in plan to lie longitudinally under the human foot from a point under the heel thereof to a point under the ball of the foot, and to provide on its underside bearing areas at both ends. The outer edge of the plate is preferably curved to lie substantially parallel with the outer side of the foot, and its inner edge is preferably shaped approximately to follow the line of the second metatarsal and the second cuneiform bones, so that the plate is preferably narrowed in plan at its waist where it underlies portions of the scaphoid and cuneiform bones.

Overlying the base plate 5, I provide an auxiliary plate 6 shorter than the base plate and of such width as to have its outer edge lie within the outer edge of the main plate, and at its inner edge to extend up along the high inside arch of the instep in the form of a wing extension 7. The edge of the wing 7, overhanging the inner edge of the main or base plate, is preferably slit laterally for flexibility. The two plates are made jointly to provide an arch structure substantially conforming to the instep arch, and each providing a portion of the foot bearing surface. Thus the portions of the main plate lying beyond the auxiliary plate at the ends and the outer side of the latter, are arched to conform to the corresponding portions of the foot and the auxiliary plate is arched longitudinally and curved transversely for substantial conformity with the higher portion of the instep arch defined by the under and inner surfaces of the astragalus and scaphoid bones.

The inner edge of the main plate portion at the narrowed waist thereof is preferably curved upward at 9, in conformity with the curvature of the auxiliary plate, and for strengthening purposes the main plate may be advantageously provided with a depressed bead extending along its higher arched portion. For use the plates are suitably secured together and their receiving surfaces are overlain by a cover piece 11, of appropriate shape to fit the shoe, such cover being preferably of leather with the usual skived edges.

The structure thus far described provides an advantageous arrangement whereby the longitudinal central portion of the arch, which underlies the higher part of the instep, is advantageously strengthened, and the receiving surface formed jointly by the two plates lends itself readily, in manufacture, to formation in the proper configuration to support the arch of the foot, thereby to make a very efficient and comfortable support.

For effecting most advantageous co-operation between the main and auxiliary plates so that the auxiliary plate may be adequately secured to the main plate when in use and yet be readily detachable therefrom, and so that the auxiliary plate may effectively merge into the main plate in a practically flush joint, I preferably construct

the device in the special form which I will now describe: That portion of the plate on which the ends and the outer edge of the auxiliary plate bear is depressed to a depth of substantially the thickness of the auxiliary plate so forming a recess in which the said edges of the auxiliary plate may neatly fit, leaving the foot receiving surfaces of said plates 5 and 6 flush at their joints. The end walls of the recess 12 thus provided preferably converge somewhat and merge in appropriate curves into the side wall 13, which forms a shoulder or abutment against which the outer edge of the auxiliary plate may bear. The leather cover piece is preferably secured to the main plate only, so as to form with said main plate a pocket into which the auxiliary plate may be readily inserted and from which it is detachable. 20 Preferably two rivets 14 located near the inner edge of the main plate and close to the end wall of the recess 12, to secure the cover piece to the main plate. In such position the rivets 14 act as a guiding means to direct 25 the insertion of the auxiliary plate into position of use, from the inner side of the device. To obviate all possibility of the outer edge of the auxiliary plate riding over the shoulder 13 and taking an improper position 30 with respect to the main plate 5, I provide within the confines of the recess 12, near the wall 13, a flat headed rivet 15 and provide in the auxiliary plate 6 a corresponding notch 16, with its edges beveled as at 17, so that, 35 as shown in Fig. 2, the head of the rivet 15 lying substantially flush with the top of the auxiliary plate 6, may act as an effective retainer for said auxiliary plate.

It is obviously advantageous that an instep arch support be readily adjustable to the foot of the individual user and this desideratum is subserved by the construction described. Manifestly the auxiliary plate 6 may be readily detached from its position 45 in use; may be easily formed to the desirable curvature to fit the highest part of the instep arch; and further, for elevation or depression of the higher side of the arch the inner edge 9 of the main plate, may be 50 raised or lowered thereby to change the effective bearing point of the auxiliary plate, and fixing to a certain extent the desired adjustment of the auxiliary member. When proper adjustment is made the auxiliary plate may be readily slipped back into its pocket, and detained against accidental displacement by the positioning means described. If desired the main plate may be sold in conjunction with a plurality of differently arched auxiliary plates, so that the user may select the auxiliary plate of conformation best suited to his feet.

While I have herein described an embodiment of my invention it will be apparent to those skilled in the art that changes may be

made in the details thereof without departure from the spirit of my invention and within the scope of the appended claims.

What I claim is:

1. In an instep arch support, the combination of a main plate arranged to bear at its ends on the sole of a shoe, said main plate having a portion of its upper surface recessed intermediate its ends, said recess extending through the inner side of the main plate only, and an auxiliary plate having a portion shaped to fit within said recess and having a wing extension beyond the inner edge of the main plate, the inner edge portion of the main plate meeting said auxiliary plate at an angle thereto. 70

2. In an instep arch support, the combination of a main plate arranged to bear at its ends on the sole of a shoe, said main plate having a portion of its upper surface recessed intermediate its ends, said recess opening to the inner side only of the main plate, an auxiliary plate having one portion shaped to conform to the recessed portion of the main plate and having a wing extension beyond the inner edge of the main plate, and means carried by the main plate and positioned at the ends of the recessed portion to coöperate with the edges of the auxiliary plate to prevent vertical movement thereof. 85

3. In an instep arch support, the combination of a main plate arranged to bear at its ends on the sole of a shoe, said main plate having a portion of its upper surface recessed intermediate its ends, said recess opening to the inner side only of the main plate, and an auxiliary plate having one portion shaped to conform to the outlines of the recessed portion of the main plate and having a wing extension beyond the inner edge of said main plate, the main plate being sharply upturned transversely at its inner edge, and provided with a longitudinal groove at the base of the upturned portion, and the auxiliary plate having a transverse curvature less than that of the upturned portion of the main plate. 95

4. In an instep arch support, a main plate arranged to bear at its ends on the sole of a shoe, said main plate having a portion of its upper surface recessed intermediate its ends, said recess opening to the inner side only of the main plate, a cover piece overlying said main plate and attached thereto near the ends of said recessed portion of the main plate, and an auxiliary plate having one portion shaped to conform to the recessed portion of the main plate, and having a wing extension beyond the inner edge of the main plate. 115

5. In an arch support, the combination of a main plate arranged to bear at its ends on the sole of a shoe, said main plate having a portion of its upper surface recessed intermediate its ends, said recess extending 120

through the inner side of the main plate only, a cover piece overlying said main plate and attached thereto near the ends of the recessed portion forming therewith a pocket, 5 and an auxiliary plate having one portion shaped to fit the said pocket, the inner edge of the main plate having an up-turned portion and the auxiliary plate having a wing extension beyond the inner edge of the main 10 plate, said auxiliary plate bearing on the up-

turned edge of the inner plate and means detachably securing the inner edge of the auxiliary plate to the main plate.

In testimony whereof I hereunto set my hand in the presence of two witnesses.

WILLIAM M. SCHOLL.
